UNITED STATES PATENT OFFICE.

HARRY LANDSIEDEL, OF POPLAR BLUFF, MISSOURI, ASSIGNOR TO DALTON ADDING MACHINE COMPANY, OF ST. LOUIS, MISSOURI, A CORPORATION OF MISSOURI.

ADDING AND RECORDING MACHINE.

1,103,300.

Specification of Letters Patent. Patented July 14, 1914.

Application filed February 1, 1912. Serial No. 674,758.

To all whom it may concern:

Be it known that I, HARRY LANDSIEDEL, a citizen of the United States, residing at Poplar Bluff, county of Butler, and State of Missouri, have invented a new and useful Adding and Recording Machine, of which the following is a specification.

This invention relates to adding and recording machines and its object is to provide in combination with the recording and operating mechanism, an improved ribbon operating mechanism, and automatic means for reversing the movement of the ribbon.

Another object is to provide ribbon spools and a laterally-movable rotary shaft, with suitable gears whereby the shaft may be entrained with said spools respectively, with provision for automatically effecting the lateral movement of the shaft effectively to rotate the other spool when the time for reversing the movement of the ribbon arrives.

Other objects will appear from the following description frequent reference being made to the accompanying drawings in which I have shown one embodiment of my invention and in which—

Figure 1 is a side elevation of a well known adding and recording machine containing my improved ribbon mechanism, the case of the machine being in section in order to disclose the mechanism contained therein. Fig. 2 is a plan view illustrating the arrangement of the laterally-movable shaft which operates the ribbon spools. Fig. 3 is a sectional view on the line 3—3 of Fig. 5. Fig. 4 is a sectional view on the line 4—4 of Fig. 2. Fig. 5 is an enlarged view of a part of the spool operating shaft illustrating the driving ratchet and the centering and holding device coöperating with the shaft to prevent said shaft from being shifted laterally by the resistance of the spool shafts. Figs. 6 and 7 are detailed views of the centering and holding device which coöperates with the spool operating shaft. Fig. 8 is a sectional view of the centering and holding device taken approximately on the line 8—8 of Fig. 5. Fig. 9 is an enlarged rear view of the ribbon spools and the operating mechanism. Fig. 10 is a sectional view of one of the ribbon spools and its support. Fig. 11 is a plan view of one of the ribbon spools. Figs. 12, 13 and 14 are detailed views illustrating the means by which the ratchet wheel

which rotates the drive shaft also shifts the drive shaft laterally to reverse the movement of the ribbon.

I have illustrated my invention embodied in an adding and recording machine known commercially as the "Dalton" adding machine, which is constructed in substantial conformity to the adding department of the combined adding and writing machine constituting the subject-matter of Hopkins Patent No. 1039130, dated September 24, 1912, the application for which was filed January 24, 1903. In said machine there is a main shaft 1, rocked through operation of a handle or lever 2 and having link connection 3, which, when operated, causes the type-carriers 4 to be reciprocated adjacent to the platen mounted in the paper carriage 5. The link 3 which is operated by the rock shaft 1 operates a part 6 by which the shaft controlling the ribbon spools is rotated through connections hereinafter described.

Near each side of the machine and in front of the paper carriage is a ribbon spool-case or housing 7, within which the ribbon spools are contained and operated and from which the ribbon is fed across the machine near the platen which is mounted in the paper carriage. On the case of the machine below each ribbon spool-case 7 is formed a bearing 8 (Fig. 10). In each bearing 8 is journaled a small shaft 9 having an annular flange 10 operating against the case and preventing the shaft from working out of the bearing. Above the flanges 10 the shafts 9 have reduced portions 11 on each of which is a locking pin 12 arranged to engage in a slot or notch in a collar or sleeve 13 fitting over said reduced portion. On the lower end of each of the collars or sleeves 13 is a circular plate 14, said plates constituting the lower ends and confining walls of the spools. A cylindrical spool 15 encircles each of the collars or sleeves 13 and is inter-locked with the lower spool-wall 14, as shown at 16 in Fig. 10. An upper end or confining wall for each spool is provided in the form of a circular plate 17 having a knob 18 for manual engagement for purposes of removal, etc., said walls or ends being inter-locked with the cylindrical spool bodies, as shown at 19. A beveled gear 20 is attached to the lower end of each of the spool shafts 9, said gears being within the case of the machine

and constituting the means for rotating the spools mounted on said shafts effectively to move the ribbon across the machine.

The shaft 21 is supported in bearings 22 removably mounted in the arms 23 attached to the frame parts 24 of the machine. Said shaft is revoluble and laterally movable in said bearings and is supported in such position that the type-carriers 4 operate between said shaft and the platen (Fig. 1). A beveled pinion 25 is secured to each end of the shaft 21, said pinions being arranged and adapted to mesh with the gears 20, respectively, on the spool shafts 9, so that when said shaft 21 is rotated motion will also be imparted to one of the spool shafts effectively to wind the ribbon onto the spool of said spool shaft so operated and to draw the ribbon from the spool at the opposite side of the machine. A ratchet wheel 26 is mounted on the shaft 21 having frictional engagement with said shaft of sufficient strength and resistance to rotate said shaft when the ratchet wheel is rotated. In other words, the ratchet wheel 26 may be rotated independently of the shaft 21 but only when the resistance to the rotation of the shaft 21 is much greater than that encountered when operating the ribbon spools to draw the ribbon from one spool to the other; when the resistance encountered is only that encountered in operating the ribbon spools to move the ribbon the frictional engagement between the ratchet wheel 26 and the shaft 21 is sufficient to rotate the shaft, especially since the said ratchet wheel is provided with associated coöperating parts presently described. The ratchet wheel 26 extends into and operates within a groove 27 in an adjacent member 28. An arm 29 is pivotally supported by the shaft 21 and supports the front end of a link 30 having pin-and-slot connection 31 with another link 32 whose rear end is pivoted to the movable part 6 which is operated back and forth by the link 3 at each operation of the recording mechanism, including the type-carriers 4 and the controlling handle 2. These connections reciprocate the link composed of the two parts 30 and 32 at each operation of the recording mechanism. A spring 33 connecting the two parts of the link 30-32 holds said members extended to the greatest length permitted by the pin-and-slot connection 31 and permits the part 32 to move forwardly independent of the part 30 when too great resistance is encountered by said part 30, such, for instance, as when the ribbon spools become locked from any cause. A pawl 34 is supported by the arm 29 and operates upon the ratchet wheel 26 thereby rotating said ratchet wheel, and the shaft 21 with which it is frictionally engaged, forwardly at each operation of the recording mechanism. This 65 rotation of the shaft 21 also rotates the rib-

bon spool shaft 9 with which said shaft 21 is entrained effectively to operate the ribbon. Backward rotation of the ratchet wheel 26 on the shaft 21 is prevented by a pawl 35 engaging with and locking said ratchet wheel against backward or reverse operation. A cam 36 is rigid with each side of the ratchet wheel 26 and two diametrically opposite pins 37 project from the shaft 21, one of said pins being at each side of the ratchet wheel 26. When the recording mechanism is operated effectively to rotate the ratchet wheel 26, as above described, the cam 36, on one side of said wheel, will engage against the pin 37 on the shaft 21, which engagement, in addition to the frictional engagement between the ratchet wheel on said shaft 21, is sufficient to prevent independent rotation of the ratchet wheel while the ribbon is movable.

When one of the ribbon spools becomes filled and the other entirely empty the empty spool, to which the ribbon is attached, can be rotated no further and the ribbon stretches and prevents further rotation of the filled spool with which the operating shaft 21 is entrained. Additional operating of the recording mechanism, therefore, results in independent rotation of the ratchet wheel 26 on the shaft 21 and this independent rotation of said ratchet wheel operates the cam 36 against the pin 37 on said shaft 21. Since the wheel 26 is not laterally-movable and since the shaft 21 is laterally-inovable this operation of the cam 36 against the pin 37 on said shaft 21 moves said shaft 21 laterally in its bearings effectively to entrain one of the pinions 25 with the gear 20 connected to the empty ribbon spool and to disconnect the other pinions 25 from the filled-up ribbon spool. This lateral movement of the shaft 21 brings the other pin 37 against the cam 36 on the opposite side of the wheel 26 so that said pin and said cam coöperate to assist in operating independent rotation of the ratchet wheel on the shaft 21 until the other ribbon spool becomes filled and the shaft is again moved laterally because of the resultant locking of the shaft against further rotation until disengaged from the filled-up spool. This lateral movement of the shaft 21, effectively to reverse the operation of the ribbon, it will be observed, is automatically effected when one spool becomes entirely empty whatever may be the length of the ribbon.

In connection with the shaft 21 I have provided a "centering" and holding device, which coöperates with the cams 36 to position the said shaft at each lateral movement thereof, and also acts independently to hold the shaft from being moved by the resistance of the spool shaft. A collar 38 is attached to the shaft 21 and is provided with peripheral grooves or channels which form an attenu-

ated rib or flange 39 (Figs. 5, 6 and 7). A yoke or bracket 40 is pivoted to a support 41 which, in the present instance, is one of the arms 23 below the shaft 21. A triangular hole 42 is formed in each side of the yoke or bracket 40 and in said holes a roller 43 is journaled. A spring 44 is connected to the yoke or bracket 40 and holds the roller 43 in one or the other of the grooves which form the rib 39. When the shaft 21 is moved laterally the rib 39 moves across the roller 43 to the other side of said roller and the spring 44 presses the said roller 43 against the oblique wall or side of said rib 39 and assists in moving and positioning the shaft 21 until the roller becomes seated in one or the other positions shown in Figs. 6 and 7. This effects the proper connection between the pinions 25 and the wheels 20, respectively, when the shaft 21 is moved laterally.

I am aware that there may be various modifications and departures from the mechanical construction and arrangement of the mechanism without any departure from the spirit and scope of the invention. I do not restrict myself to identical features of construction and arrangement, but—

What I claim and desire to secure by Letters Patent is—

30 1. The combination with two spool shafts, of a drive shaft, a ratchet wheel on said drive shaft, means for actuating said ratchet wheel effectively to rotate said drive shaft, means preventing said ratchet wheel from moving laterally with said drive shaft, means on one side of said ratchet wheel whereby said wheel will actuate said drive shaft laterally in one direction under predetermined conditions, and means on the other side of said ratchet wheel whereby said wheel will actuate said drive shaft laterally in the opposite direction under predetermined conditions.

45 2. The combination with two spool shafts, and a pinion on each of said shafts, of a drive shaft, pinions on said drive shaft adapted to mesh with the pinions of said spool shaft alternately, a ratchet wheel mounted on said drive shaft, means for actuating said ratchet wheel effectively to rotate said drive shaft, cams attached to and controlled by said ratchet wheel, projections on said shaft arranged to be engaged by said cams to move said shaft laterally as required 55 to mesh the pinions thereon alternately with the pinions on said spool shafts, and means preventing said ratchet wheel from moving laterally with said drive shaft.

60 3. The combination with two spool shafts, and a pinion on each of said shafts, of a drive shaft, pinions on said drive shaft adapted to mesh with the pinions on said spool shafts alternately, a ratchet wheel mounted on said drive shaft, means for actuating said ratchet wheel effectively to ro-

70 late said drive shaft, projections on said drive shaft, cams on said ratchet wheel arranged to engage said projections effectively to shift said drive shaft laterally thereby meshing the pinions on said drive shaft alternately with the pinions on said spool shafts, and means preventing said ratchet wheel from moving laterally when said shaft is shifted as aforesaid, substantially as specified.

75 4. The combination with two spool shafts, and a pinion on each of said shafts, of a drive shaft, pinions on said drive shaft adapted to mesh with the pinions on said spool shafts alternately, a ratchet wheel mounted on said drive shaft, means for actuating said ratchet wheel effectively to rotate said drive shaft, a projection on said shaft at each side of said wheel and means actuated by said ratchet wheel to engage said projections to shift said drive shaft laterally to mesh the pinions thereon alternately with the pinions on said spool shaft, substantially as specified.

80 5. The combination with two spool shafts, and a beveled pinion on each of said shafts, of a drive shaft, beveled pinions on said drive shaft adapted to mesh with the pinions on said spool shafts alternately and thereby positively rotate said spool shafts, 85 a ratchet wheel mounted on said drive shaft, means for actuating said ratchet wheel effectively to rotate said drive shaft, a device preventing said drive shaft from being moved laterally by the resistance of the 90 spool shafts, and cams on opposite sides of said ratchet wheel actuated by said ratchet wheel for moving said drive shaft laterally against the resistance of said device effectively to mesh the pinions on said drive 95 shaft alternately with the pinions on said spool shafts.

100 6. The combination with two ribbon spools, and a shaft for actuating said spools alternately arranged to be rotated and alternately shifted laterally in opposite directions as required to enable said shaft to actuate said spools alternately, of a ratchet wheel mounted on said shaft, means for actuating said ratchet wheel effectively to rotate said 105 shaft, cams actuated by said ratchet wheel, projections on said shaft arranged to be engaged by said cams whereby said shaft will be alternately shifted laterally in opposite directions, and means preventing said 110 ratchet wheel from moving laterally with said shaft.

115 7. The combination with a laterally movable shaft, a ratchet wheel mounted on said shaft, and means for actuating said ratchet wheel to rotate said shaft, of a device engaged by said ratchet wheel for moving said shaft laterally in one direction, another device engaged by said ratchet wheel for moving said shaft laterally in the other di- 120 125 130

rection, and a separate device for preventing accidental lateral movement of said shaft.

8. The combination with two ribbon spools, and a shaft for actuating said spools alternately arranged to be rotated and alternately shifted laterally in opposite directions as required to enable said shaft to actuate said spools alternately, of a device for holding said shaft in whatever adjustment it may be placed, a ratchet wheel for rotating said shaft, a device at one side of and operated by said ratchet wheel for moving said shaft laterally in opposition to said holding device, and a device on the other side of and operated by said ratchet wheel for moving said shaft laterally in a direction opposite to which it is moved by said first-named device.

9. The combination with two spools, and a shaft arranged to be rotated and to be moved laterally to actuate said spools alternately, of a ratchet wheel mounted on said shaft, means for actuating said ratchet wheel effectively to rotate said shaft, cams on said wheel, projections on said shaft arranged to be engaged by said cams effectively to shift said shaft laterally with respect to said wheel, and a device holding said wheel from lateral movement, substantially as specified.

10. In a recording machine, the combination with two spools, and a pinion for rotating each of said spools, of a drive shaft, pinions on said drive shaft adapted to mesh with the first-named pinions alternately, a wheel for rotating said drive shaft, cams on opposite sides of said wheel, means mounted

on said drive shaft at one side of said wheel adapted to be engaged by one of said cams to shift said shaft laterally with respect to said wheel as required to mesh one of said pinions on said shaft with one of the first-named pinions, and means mounted on said drive shaft at the other side of said wheel adapted to be engaged by the other of said cams to shift said shaft laterally with respect to said wheel as required to mesh the other pinion on said shaft with the other one of the first-named pinions.

11. In a recording machine, the combination with two spools, a ribbon adapted to be wound from one to the other of said spools alternately, and a pinion for rotating each of said spools, of a drive shaft, pinions on said drive shaft adapted to mesh with the first-named pinions alternately to reverse the movement of the ribbon, means for rotating said drive shaft, projections on said shaft at opposite sides of said rotating means, means controlled by said rotating means for engaging said projections to shift said drive shaft laterally effectively to mesh one of the pinions thereon with one or the other of said first-named pinions, and a device for preventing lateral movement of said rotating means.

In witness whereof, I have signed this specification in the presence of two subscribing witnesses.

HARRY LANDSIEDEL.
